UNITED STATES PATENT OFFICE.

ALBERT HENRY MAXWELL, OF COUNCIL BLUFFS, IOWA, AND GORDON C. DIMOCK, OF NEWMAN GROVE, NEBRASKA.

DRAFT-EQUALIZER.

SPECIFICATION forming part of Letters Patent No. 621,837, dated March 28, 1899.

Application filed December 3, 1898. Serial No. 698,190. (No model.)

To all whom it may concern:

Be it known that we, ALBERT HENRY MAXWELL, residing at Council Bluffs, in the county of Pottawattamie and State of Iowa, and GORDON C. DIMOCK, residing at Newman Grove, in the county of Madison and State of Nebraska, citizens of the United States, have invented a new and useful Draft-Equalizer, of which the following is a specification.

10 The invention relates to improvements in draft-equalizers.

The object of the present invention is to improve the construction of draft-equalizers and to provide a simple and inexpensive one designed for use on plows and adapted to equalize the draft of four horses and enable one of them to walk in the furrow and three on unplowed land.

15 A further object of the invention is to prevent any side draft and to enable the parts to be adjusted so as to equalize the draft between horses of unequal weight.

The invention consists in the construction and novel combination and arrangement of 20 parts, as hereinafter fully described, illustrated in the accompanying drawings, and pointed out in the claims hereto appended.

In the drawings, Figure 1 is a perspective view of a draft-equalizer constructed in accordance with this invention. Fig. 2 is a transverse sectional view. Fig. 3 is a sectional view taken at right angles to Fig. 2. Fig. 4 is a detail plan view illustrating the arrangement of the equalizing-levers.

25 Like numerals of reference designate corresponding parts in all the figures of the drawings.

1 designates a main whiffletree centrally connected with a plow-beam by means of a 30 clip or clevis 2 and having one end pivoted, by means of a bolt 3 or other suitable fastening device, between a pair of straps 4, which are similarly secured to the upper and lower faces of the doubletree 5, whereby the latter 35 is connected with the adjacent end of the main whiffletree 1. Singletrees 6 and 7 are pivoted to the ends of the doubletree 5 or otherwise connected to the same, and the outer horse, which is designed to be hitched 40 to the singletree 6, walks in a furrow, while

the adjacent horse travels nearly in front of the plow on unplowed land. The other end of the main whiffletree 1 has a straight equalizing-lever 8, connected to it by a pivot 9, located at one side of the center of the lever 8, 55 and the inner end of the straight equalizing-lever 8 is connected by a pair of links or straps 10 with a front equalizing-lever 11, located in advance of the rear equalizing-lever 8, as shown. The levers 8 and 11 extend longitudinally of the main whiffletree 1, and the front equalizing-lever is provided at its inner end with a curved arm 12, extending rearward and connected by a pivot 13 to the main whiffletree 1 at a point adjacent to the pivot 14 of the strap or clevis 2. The rear equalizing-lever is provided at its lower face with a spacing plate or piece 15, terminating short of its inner end and providing a space between the same and the main whiffletree 1 for the 70 head of the pivot of the straps or links 10. The arrangement of the front and rear levers 8 and 11 equalizes the draft and prevents any side draft. The main whiffletree 1 is provided at its center with a series of perforations 16, 75 adapted to receive the pivots 13 and 14, and when one or two of the draft-animals are of less weight than the others the heavier animals are attached to the singletrees 6 and 7 and the lighter animals are hitched to singletrees 17 and 18, located at the outer ends of the levers 8 and 11, and the pivots 13 and 14 are adjusted toward the lighter animals. The outer ends of the levers 8 and 11 are provided with perforations 19 and 20 to permit 80 the adjustment of the singletrees 17 and 18, and the singletree 17 is connected with the rear equalizing-lever by a pair of straps or links 21.

85 The invention has the following advantages: The draft-equalizer, which is simple and inexpensive in construction, is designed especially for plows and is adapted to equalize the draft of four horses and enable one of them to walk in the furrow and the other three 90 on unplowed land, and it absolutely prevents any side draft. The parts are also capable of adjustment, so as to equalize draft when one or more of the horses are of less weight than the others. 95

Changes in the form, proportion, and minor details of construction may be resorted to without departing from the spirit or sacrificing any of the advantages of this invention.

5 What is claimed is—

1. A draft-equalizer comprising a main transverse whiffletree provided with a device arranged between its ends for connecting it with the beam of a plow, singletrees connected with one end of the main whiffletree, the transversely-disposed rear equalizing-lever 8 pivoted to the other end of the main whiffletree, the front equalizing-lever 11 located in advance of the lever 8, and disposed transversely, its inner end being provided with a rearwardly-disposed arm pivoted to the main whiffletree, means for connecting the inner end of the rear equalizing-lever with the front equalizing-lever, and singletrees connected 20 with the outer ends of the equalizing-levers, substantially as described.

2. A draft-equalizer comprising a main whiffletree provided at its center with a series of perforations, a centrally-arranged fastening device provided with a pivot passing 25

through one of the said perforations, a doubletree provided with singletrees and connected with one end of the main whiffletree, a rear equalizing-lever pivoted to the other end of the main whiffletree, a front equalizing-lever having a rearwardly-disposed arm pivoted to the main whiffletree with its pivot arranged in one of the perforations thereof, means for connecting the inner end of the rear equalizing-lever with the front equalizing-lever, and singletrees adjustably connected with the outer ends of the equalizing-levers, substantially as described. 30

In testimony that we claim the foregoing as our own we have hereto affixed our signatures 35 in the presence of witnesses.

ALBERT HENRY MAXWELL.
GORDON C. DIMOCK.
